MARKING MACHINE

Victor Toivo Johnson, Los Angeles, Calif.

Application June 26, 1933, Serial No. 677,693

7 Claims. (Cl. 275—2)

My invention relates to marking machine, and the objects of my invention are:

First, to provide a machine which is particularly adapted to deposit a strip of powder along the ground;

Second to provide a machine of this class which ensures proper and uniform feeding of the powder even though the powder be caked or in lumps;

Third, to provide a machine of this class which incorporates a novel means of working the powder or the like into the discharging end of the machine so that the discharging end remains full of the powder until the bin or hopper thereabouts has been completely emptied;

Fourth, to provide a machine of this class which incorporates a novel means whereby the feeding mechanism may be set into operation or rendered inoperative readily and quickly as desired, thus enabling the machine to be wheeled from place to place; and

Fifth, to provide on the whole a novelly constructed marking machine which is simple of construction and operation, durable, efficient in its action, and which will not readily deteriorate or get out of order.

With these and other objects in view as will appear hereinafter, my invention consists of certain novel features of construction, combination, and arrangement of parts and portions as will be hereinafter described in detail and particularly set forth in the appended claims, reference being had to the accompanying drawings and to the characters of reference thereon which form a part of this application in which:

Figure 1 is a side elevational view of the marking machine with one wheel removed; Fig. 2 is an enlarged fragmentary transverse sectional view through 2—2 of Fig. 1; Fig. 3 is an enlarged partial-sectional partial-plan view through 3—3 of Fig. 2; Fig. 4 is another enlarged sectional view through 4—4 of Fig. 2.

Similar characters of reference refer to similar parts and portions throughout the several views of the drawings.

Hopper 1, nozzle shell 2, brackets 3, shaft 4, wheels 5, screen 6, impeller sleeve 7, impellers 8, clutch sleeve 9, clutch lever 10, support bar 11, regulator gate 12, regulator lever 13, connecting screw 14, nozzle 15, hinge 16, clip 17, shaker plates 18, handle bars 19, and supporting foot 20 constitute the principal parts and portions of my novel marking machine.

A hopper 1 is provided which is substantially square in section, and comprises a vertically walled upper portion 1a and a converging lower portion 1b. The upper end of the hopper 1 is closed by a suitable lid or cover 1c. The lower or converging end of the hopper 1 is joined to a nozzle shell 2 which is substantially cylindrical in form

with its axis extending horizontally and laterally with respect to the hopper. The upper side of the nozzle shell 2 is cut away and merges into the converging portion 1b of the hopper.

From the lateral sides of the hopper 1 extend depending brackets 3 which are provided with alined bearings 3a at their lower extremities adapted to receive the shaft 4. The shaft 4 extends through the nozzle shell 2 in concentric relation with its axis. The extremities of the shaft 4 are provided with wheels 5 which are secured thereto whereby the wheels and shaft turn as a unit. The lower side of the nozzle shell 2 is provided with a slot 2a therein which is of constant width and extends axially.

An impeller sleeve 7 is mounted on the shaft 4 at the portion thereof extending through the nozzle shell 2. The sleeve 7 protrudes with the shaft through the ends of the nozzle shell 2. The portion of the impeller sleeve within the nozzle shell 2 is provided with several impellers 8 which are in the form of circular disks disposed in parallel relation with each other but in oblique relation with the impeller sleeve 7. As the impeller sleeve turns, the lower portions of the several impellers oscillate laterally, that is, axially within the nozzle shell.

The impeller sleeve is revolvably mounted with respect to the shaft 4 and is held against axial movement relative thereto by means of collars 7a disposed within the ends of the nozzle shell 2. At one protruding end the impeller sleeve is provided with a series of axially extending slots 7b forming a clutch element. The adjacent exposed portion of the shaft 4 receives a clutch sleeve 9 which is held in slideable relation therewith by means of a pin and slot arrangement designated 9a. The axial end of the sleeve 9 facing the impeller sleeve 7 is provided with a clutch element 9b adapted to co-act with the clutch element 7b, as shown best in Figs. 2 and 3. The clutch sleeve 9 is provided with an annular channel 9c which receives a forked end 10a of a clutch lever 10. The clutch lever 10 extends backwardly from the shaft 4, and is journaled intermediate its ends from a supporting bar 11. The support bar 11 is substantially U-shaped and secured by its ends to the bracket 3, and disposed so as to extend along the rear lower side of the bin 1.

The screen slot 2a of the nozzle shell is adapted to be controlled by a regulator gate 12. Said gate comprises an arcuate gate portion 12a extending axially along and fitting adjacent the bottom of the nozzle shell 2. The ends of the gate portion 12a are provided with upturned arms 12b which journal on the impeller sleeve 7 between the collars 7a and the ends of the nozzle shell 2. Journaled on the impeller sleeve 7 at the end thereof opposite from the clutch element 7b, is a regulator lever 13 which extends 60

downwardly therefrom forming a handle 13a at its lower extremity. The corresponding end of the nozzle shell 2 is provided with an arcuate slot 2b therein adapted at all times to be covered by the upper portion of the regulator lever 13. A connecting screw 14 extends through the slot 2b so as to join the lever 13 with the corresponding arm 12b of the regulator gate 12, thus by shifting the lever arcuately, the exposed portion 10 of the slot 2a may be varied.

The nozzle shell 2 is provided with a nozzle 15 which has an upper portion that conforms to the lower portion of a nozzle shell and connected thereto at one side by means of a hinge 16 and at the opposite side by means of a clip 17, as shown best in Fig. 4. The lower end of the nozzle 15 converges to a rectangular opening of the desired width and length. The upper portion of the nozzle 15 carries a screen 6 which is adapted to conform to and fit against the lower side of the nozzle shell 2 so as to cover the slot 2a.

Disposed on the forward and back sides respectively of the converging lower portions 1b of the bin 1 are a pair of shaker plates 18. Each shaker plate is substantially triangular with an apex pointing downwardly. This apex is provided with a forked portion 18a which is adapted to straddle the central impeller 8 so that as the periphery of the impeller moves back and forth, the lower end of the shaker plate is shifted likewise. Each shaker plate 18 is journaled intermediate its upper end on a pin 18b so that the plate oscillates about said pin as its lower end is shifted laterally. The plates 18 occupy approximately the entire rear and forward ends of the converging portion 1b, thus movement of the impeller causes the shaker plate to work the powder or other material in the bin towards the nozzle shell 2.

The lateral sides of the hopper 1 are provided with handle bars 19 which extend upwardly and backwardly to form a handle, and downwardly and forwardly to form supporting legs 19a. Also the rear lower side of the hopper is provided with a downwardly and rearwardly extending supporting leg 20. The legs 19a and 20 terminate upwardly from the bottom of the wheels 5.

Though I have shown and described a particular construction, combination, and arrangement of parts and portions, I do not wish to be limited to this particular construction, combination, and arrangement, but desire to include in the scope of my invention the construction, combination, and arrangement substantially as set forth in the appended claims.

Having thus described my invention, what I claim as new and desire to secure by Letters Patent is:

1. In a marking machine, a hopper, a truck means for carrying said hopper, a nozzle means at the lower end of said hopper, said truck means including a shaft extending through said nozzle means, agitators mounted on said shaft within said nozzle means, and plates shiftably mounted within said hopper contiguous to the sides thereof and extending into engagement with said agitators for shifting therewith and facilitate feeding of the contents of said hopper into said nozzle means.

2. In a marking machine, a hopper, a truck means for carrying said hopper, a nozzle shell at the lower end of said hopper arranged to receive the contents thereof, a screen outlet for said nozzle shell, said truck means including a

shaft extending within said nozzle shell, agitators mounted on said shaft within said nozzle shell adapted to work the contents thereof over and through said screen outlet, and plates shiftably mounted within said hopper contiguous to the sides thereof and extending into engagement with said agitators for shifting therewith and to facilitate feeding of the contents of said hopper into said nozzle shell.

3. A marking machine comprising, a hopper, a nozzle shell at the lower end thereof, a revoluble shaft extending through said nozzle shell, impeller disks obliquely mounted on said shaft whereby their peripheries oscillate upon rotation of said shaft, said nozzle shell having a discharge opening and said disks extending into contiguous relation thereto, and shaker members pivotally mounted contiguous to the sides of said hopper including means engageable with the periphery of an impeller whereby movement of said impellers cause oscillation of said shaker members.

4. In a marking machine, a hopper, a nozzle shell at the lower end thereof, a revoluble shaft extending through said nozzle shell, impeller disks obliquely mounted on said shaft whereby their peripheries oscillate upon rotation of said shaft, said nozzle shell having a discharge opening and said disks extending into contiguous relation thereto, shaker plates pivotally mounted contiguous to the sides of said hopper including means engageable with the periphery of an impeller whereby movement of said impellers cause oscillation of said shaker plates, and a truck for carrying said hopper including means engageable with said shaft for actuating the same as said hopper is carried by said truck.

5. In a marking machine, a hopper, a nozzle shell at the lower end thereof, a revoluble shaft extending through said nozzle shell, impeller disks obliquely mounted on said shaft whereby their peripheries oscillate upon rotation of said shaft, said nozzle shell having a discharge opening and said disks extending into contiguous relation thereto, shaker plates pivotally mounted contiguous to the sides of said hopper including means engageable with the periphery of an impeller whereby movement of said impellers cause oscillation of said shaker plates, a truck for carrying said hopper including means engageable with said shaft for actuating the same as said hopper is carried by said truck, clutch means interposed between said means and said shaft, and a regulating gate for the discharge opening of said nozzle shell.

6. In a marking machine, a revoluble shaft, impeller disks obliquely mounted on said shaft whereby their peripheries oscillate upon rotation of said shaft, and pivotally mounted shaker plates with slot portions engageable with the peripheries of an impeller disk whereby movement of said impellers causes oscillation of said shaker plates.

7. In a marking machine wherein there is a hopper mounted on a truck with a shaft, the combination with said hopper and shaft of impeller disks obliquely mounted on said shaft whereby their peripheries oscillate upon rotation of said shaft, and shaker plates pivotally mounted contiguous to the sides of said hopper including means engageable with the periphery of an impeller whereby movement of said impellers causes oscillation of said shaker plates.

VICTOR TOIVO JOHNSON.
